UNITED STATES PATENT OFFICE

168,097

SPECTACLE FRONT

Samu-El Ish-Shalom, New York, N. Y.

Application May 9, 1952, Serial No. 19,645

Term of patent 14 years

(Cl. D57—1)

To all whom it may concern:

Be it known that I, Samu-El Ish-Shalom, a citizen of the United States of America, residing at New York, N. Y., have invented a new, original, and ornamental Design for a Spectacle Front, of which the following is a specification, reference being had to the accompanying drawings, forming a part hereof.

Figure 1 is a front elevational view of a spectacle front showing my new design, and

Figure 2 is a perspective view in exploded form on an enlarged scale showing the elements of one of the ornaments shown in full lines in Fig. 1.

The essential features of my design reside in the ornamentation shown in full lines.

I claim:

The ornamental design for a spectacle front, as shown and described.

SAMU-EL ISH-SHALOM.
